UNITED STATES PATENT OFFICE.

OLIVER P. WENTWORTH, OF FORGAN, OKLAHOMA.

WHEAT-STACKER.

1,306,842.

Specification of Letters Patent. Patented June 17, 1919.

Application filed March 23, 1918. Serial No. 224,271.

To all whom it may concern:

Be it known that I, OLIVER P. WENTWORTH, a citizen of the United States, residing at Forgan, in the county of Beaver and State of Oklahoma, have invented certain new and useful Improvements in Wheat-Stackers, of which the following is a specification, reference being had to the accompanying drawings.

10 This invention relates to straw stackers, and particularly to straw stackers which are used for transferring wheat from a barge to a stack. The general object of the invention is to 15 provide a stacker of this character of a very simple form and which is positively controlled at all times, and which is so constructed that the sling on a barge may be lifted and discharged into a lifting and 20 dumping rack and in which the racks may then be lifted and dumped onto a stack.

One of the objects of the invention is to provide means whereby the wheat or other grain for threshing may be lifted vertically 25 and then discharged onto the stack, so as to permit a vertical stack to be built.

A further object of this invention is to provide a construction of this character which will operate at the side of the stack 30 and which may be shifted parallel to the stack at will so as to operate in connection with a stack of any desired length or, in other words, to build a stack of any desired length.

35 Still another object is to provide a machine of this character including a receiving and discharging rack, and provide means whereby the rack may be hoisted to a predetermined height and then dumped automatically, and in this connection to provide 40 means whereby the dumping of the rack may be controlled so that any amount of wheat may be discharged at any desired time, the dumping rack being under positive control 45 at any point.

Another object is to provide means whereby the slings of a barge may be engaged and raised and carried into a position where the sling may be dumped into the rack, and provide means whereby the sling may be returned to its position over the barge and returned to the barge.

Still another object is to provide improved means whereby the hoisting and dumping machine may be held from overturning under strain.

Other objects will appear in the course of the following description.

My invention is illustrated in the accompanying drawings, wherein:

Figure 1 is a front elevation of a hay stacker constructed in accordance with my invention;

Fig. 2 is a top plan view of the construction shown in Fig. 1;

Figs. 3 and 4 are end elevations of the machine shown in Figs. 1 and 2 but on an enlarged scale and showing the rack in its receiving and in its dumping positions;

Fig. 5 is a fragmentary side elevation of the lower portion of one pair of uprights 13 showing in full lines the slide in a lowered position and in dotted lines the slide in a raised position to its full extent;

Fig. 6 is a fragmentary vertical sectional view on the line 6—6 of Fig. 5 but on a smaller scale;

Fig. 7 is a fragmentary top plan view showing the connection of the brace 17 to the uprights;

Fig. 8 is a sectional view on the line 8—8 of Fig. 7;

Fig. 9 is a diagrammatic view showing the cable for holding the machine to the ground and its engagement with the machine; and

Fig. 10 is an end view of one of the drums and its brake.

Referring to the drawings, it will be seen that my machine includes a base, preferably composed of longitudinal beams 10 and transverse beams 11, these beams being bolted together and being preferably supported on wheels 12. Attached to the inner pair of transverse beams 11 and extending upward therefrom are the vertical supports 13 and guides 14, there being two of these vertical supports and guides at each end of the machine, each pair of these guides being spaced a relatively short distance from each other and being formed on their confronting faces with guide grooves 14. The beams 13 are separated at their upper ends by means of a sleeve 15 and passing through this sleeve and the uprights 13 is a bolt 16, to which the brace 17 is operatively connected, this brace extending downward and laterally at an inclination and being engaged with converging end braces 18 which are bolted or otherwise attached to the longitudinal beams 10 of the machine. The uprights 13 are also braced by downwardly and forwardly extending braces 19 and by

- transverse downwardly and forwardly inclined rails 20 which are bolted to the uprights and at their rear ends are bolted to uprights 21. The forward ends of these rails 20 are connected by means of a longitudinally extending rail 22. Posts 23 are attached to one of the longitudinal beams 10 and extend up to the lower ends of the rails 20 and assist in supporting the same.
- 10 Extending outward from each of the uprights 13 on each end of the machine are the arms 24 which at their ends are connected to upwardly extending tension or brace rods 25 which engage with coiled springs 26 in turn engaged with the upper end of the corresponding upright 13. Preferably the arms 24 have a hinged or pivotal connection to the uprights 13.
- Disposed between the pairs of uprights 13 is the rack designated generally 27. This rack is composed of a longitudinally extending beam 28 having attached thereto the upwardly and outwardly diverging slats 29, these slats being connected by longitudinal braces in any suitable manner. The longitudinal beam 28 may be provided with trunnions 30 at its ends (see Fig. 6), and these trunnions may be formed by a longitudinally extending shaft disposed through the beam 28 and projecting beyond the ends of the beam. The trunnions 30 extend into the space between each pair of uprights 13.
- Disposed in the guide grooves 14 of each pair of guideways or uprights 13 is a slide 31 which may be made of a plate of metal and which is longitudinally slotted as at 32. The trunnion or shaft 30 passes into this slot 32 and has movement vertically in this slot.
- 40 For the purpose of raising these slides 31 and raising or lowering the rack and turning the rack to and from its dumping position, I attach to the ends of the forwardly projecting end bars 22^a of the rack, the downwardly and rearwardly extending braces 33 which extend beyond the rear-most end bar of the rack and are attached to these rearwardly extending end bars at 34. A link 35 is pivotally engaged with the rearwardly extending termination of each brace 33 and this link extends up to and is pivotally connected with the corresponding slide 31, as by means of the pin or bolt 36. It will thus be seen that when the rack is raised, the vertical movement of the rack will be transmitted through the links 35 to the upper ends of the slides 31 and that these slides will consequently move upward with the rack so long as the upward movement of the slides is not prevented, and when the upward movement of the slides is prevented, then the trunnions 30 move upward in the slots 32 and this upward movement acts to tip the rack in the manner illustrated in Fig. 4 to discharge the load.

For the purpose of adjustably limiting the upward movement of the slides, I provide the guides or uprights 13 with a plurality of perforations 37 disposed at different heights and provide stop pins 38 which are adjustable through any pair of these perforations and thus are adjustable at any desired height from the ground. This stop pin is disposed in the path of movement of the slide and when the slide reaches the stop pin the upward movement of the slide is prevented. A continued upward movement of the rack however will cause the rack to pivot upon the bolt 35^a and the rack consequently will turn to a dumping position to an extent determined by the amount of vertical movement given to the rack after the upward movements of the slides have been prevented by the stop pins 38.

The slides 31 are raised and lowered by means of cables 39 at each end of the rack. Each cable is attached at 40 to the upper end of one of the uprights at that end, then extends downward and passes through a pulley 41 attached to the end of the beam 28, then extends upward and passes over a pulley 42, and then again downward and passes over a pulley 43, from which it extends to a winding drum 44 mounted upon a shaft 45. This winding drum may be of any suitable construction and may be operated in any suitable manner. It will be seen that when the winding drum is rotated in one direction, the rack with the slides 31 will be raised and that when the upward movement of the slides has been stopped by engagement with the pins 38, the pull on the cables 39 will cause a still further upward movement of the rack and that through the links 35 and braces 33 the rack will be dumped as heretofore described.

For the purpose of holding the slides 31 from rearward movement when they have struck the pins 38, I mount upon each slide a pair of latches 46, these latches extending for a portion of their length parallel to the slot 32 but being slightly bowed inward and having their lower ends deflected to engage in a series of ratchet notches 47 formed in the confronting faces of the uprights 13. These latches 46 may be resiliently urged inward or may swing toward each other or inward by gravity. Preferably, however, they will be of resilient material and therefore be urged toward each other so that their lower ends will be disposed inward of the confronting faces of the uprights 13.

For the purpose of spreading these latches so as to cause them to engage with the notches 47, I mount upon each trunnion 48 a wedging member 49 having upwardly convergent faces disposed between the latches 46. Now when the slides 31 engage with the pins 38 and are prevented from any further upward movement, the trunnions 30 and the

wedging members 49 will travel upward in the slot 32 and will force the lower ends of the latches 46 apart so that the lower extremities of these latches will engage in the ratchet notches 47 in the manner illustrated in Fig. 5, holding the slides 31 raised while the rack is being dumped. Upon the unwinding of the hoisting cables from the winding drum 44, the rack with its trunnions will lower and the wedging members 49 will be also lowered until they release the latching members 46 and cause them to swing inward toward each other and out of engagement with the notches 47 so that when the trunnions 30 reach the lower ends of the slots 32, the continued downward movement of the rack will cause the downward movement of the slides 31 to their initial position.

For the purpose of engaging a hay sling and lifting it from a barge and carrying it over to a position above the rack where it may be dumped, I have provided the arms 24 previously referred to and I also provide a winding drum 50 loosely mounted upon the shaft 45. The arms 24, as previously stated, are hinged or pivotally mounted upon the uprights 13 so as to swing slightly in a vertical plane and each arm carries at its extremity a pulley 51. Passing over this pulley is a cable 53 which carries at its extremity a pulley 54. The cable 53 passes over a pulley mounted upon the corresponding diagonal braces, and the extremity of the cable is attached to a weight 56. The cable 53 carries at its extremity the pulley 54 over which the cable 52 passes, this cable carrying the hook 57 which is adapted to engage one end of a sling. The cable 52 passes back to the uprights 21 through a suitable pulley and downward and thence through any suitable leading pulleys to the drum 50.

With this construction it is plain that when the hooks 57 are engaged with the ends of the hay sling, and the cables 52 are wound up upon the drum 50, the blocks 54, will be drawn inward carrying with them the hooks 57 so as to carry the sling to a position above the rack and at the same time that the weights 56 will be elevated. When the sling has been discharged and the cables 52 are slackened by permitting the drum to unwind, the weights 56 will act to return the hooks and sling to a proper position over the barge so that the under sling may be connected to the hooks and the operation repeated.

For the purpose of preventing an unwinding movement of the drum 44 under the action of the weight of the rack, after the drum has been disengaged from the shaft 45, I provide a clutch in the form of a band brake 58 which encircles the drum 50 at one point, one end of the band forming

the brake being connected to a pin 58^a while the other end of the band is connected to a lever 59 pivoted intermediate its ends. The coiled contractile spring 60 acts to draw the two ends of the band together and clamp the band in frictional contact with the drum unless the lever 59 is operated. The drum 44 may be operated in any suitable manner, but if the shaft 45 is a power operated shaft, the drum 44 is loose upon this shaft 75 but is connectible to the shaft by means of ordinary clutch mechanism which is released when the rack is dumped. I prefer, however, to rotate the drum 44 by means of a cable 61 wrapped around a portion of the drum, which cable may be connected to a draft animal so that as the draft animal moves away from the supporting frame, the drum will be turned to wind up the cable thereon.

The drum 50 may also be operated by means of power applied to the shaft 45, but I have illustrated this drum also as being operated by means of a cable 62 wound upon a portion of the drum extending over a pulley 63 and connected to a draft element. I do not wish to be limited, however, to any specific means for operating these winding drums. The coiled springs 26 permit a yielding movement of the guide rods 23 95 which permits the arms 24 to adjust themselves to the strain on the cable when a sling is being lifted and hauled into position to be dumped.

It is, of course, desirable to make the machine of as light weight as possible consistent with steadiness and in order to provide for anchoring the base of the machine to the ground and yet permitting the machine to be shifted longitudinally along a stack, I provide a cable 64 which extends longitudinally over the base of the machine and is anchored at its ends by anchoring pegs 65, this cable 64 passing over pulleys 66 mounted on the frame of the machine 110 and the cable being just sufficiently tight so as to permit the machine to be shifted longitudinally and yet hold the base of the machine firmly upon the ground and preventing the base from tipping up when the rack 115 is dumping.

This stacker is designed to be constructed very largely of wood and preferably the rack is formed of the longitudinally extending beam 28 which is preferably about 120. 16 feet long, the body of the rack being formed of 1" by 4" slats set alternately to each other, thus making the rack relatively light. The machine is approximately 8 feet wide over all and the hoisting uprights will 125 ordinarily be about 16 feet high.

While I have illustrated certain details of construction which I believe to be particularly effective, it will be obvious that these details may be modified in many ways and 130

that the elements of the rack may be arranged in different ways without departing from the spirit of the invention as defined in the appended claims.

5 Having thus fully described my invention, what I claim is:—

1. A stacker including a vertically movable and rotatably mounted rack, means for applying power to the rack to hoist it to a predetermined elevation, a stop limiting the bodily upward movement of the rack, and means then causing the rotation of the rack to discharge its contents.

2. A stacker comprising a base, vertically disposed, longitudinally spaced guides mounted on the base, slides carried by said guides, a rack having divergent sides, and trunnions rotatably mounted in the slides, the slides being provided with vertical slots 10 into which said trunnions extend, power operated means for simultaneously raising the rack and the slides, adjustable means for limiting the upward movement of the slides beyond a predetermined point, and means for causing the further upward movement 20 of the trunnions within said slots to overbalance the rack and tip it to a discharging position.

3. A stacker comprising a base, vertically disposed longitudinally spaced guides mounted on the base, slides carried by said guides, a rack having divergent sides, and trunnions rotatably mounted in the slides, the slides being provided with vertical slots 30 into which said trunnions extend, power operated means for simultaneously raising the rack and the slides, adjustable means for limiting the upward movement of the slides beyond a predetermined point, means for causing the further upward movement of the trunnions within said slots to overbalance the rack and tip it to a discharging position, and means actuated by the continued upward movement of the trunnions 40 for locking the slides to the guides to prevent downward movement of the slides, said means acting upon a downward movement of the trunnions in the slots to release said locking means.

4. A stacker including a vertically movable rack having divergent sides, a vertically movable fulcrum for the rack and operatively engaging the rack to one side of the longitudinal axis thereof, means for simultaneously raising the rack and the fulcrum, and means acting to stop the upward movement of the fulcrum at a predetermined point but permitting the further upward movement of the rack to thereby cause the 50 rack to tilt upon its fulcrum and discharge its contents.

5. A stacker including a base, vertically disposed longitudinally spaced guides on the base, a rack having divergent sides disposed 60 between the guides, vertically slotted slides

mounted on the guides, the rack having trunnions extending into the slots of the slides and rotatable therein, said trunnions being disposed in the axial center of the rack, links pivotally connected to the upper 70 ends of the slides, the lower ends of the links being pivotally connected to the rack at a point rearward of the axial center of the rack, means for limiting the upward movement of the slides, and means for lifting the 75 rack with the slides until the movement of the slides is stopped and still further lifting the rack to cause the rack to tilt upon the lower ends of the links to thereby discharge the contents thereof.

6. A stacker including a base, vertically disposed longitudinally spaced guides on the base, a rack having divergent sides disposed between the guides, vertically slotted slides mounted on the guides, the rack having trunnions extending into the slots of the slides and rotatable therein, said trunnions being disposed in the axial center of the rack, links pivotally connected to the upper ends of the slides, the lower ends of the links being pivotally connected to the rack at a point rearward of the axial center of the rack, means for limiting the upward movement of the slides, means for lifting the rack with the slides until the movement of the slides is stopped and still further lifting the rack to cause the rack to tilt upon the lower ends of the links to thereby discharge the contents thereof; latches carried by the slides and engaging with the guides, and means carried by the trunnions of the rack for shifting said latches into operative position when the rack moves upward independently of the slides and releasing said latches when the rack moves downward independently of the 105 slides.

7. A stacker including a base, a pair of vertically disposed guides mounted on the base and longitudinally spaced from each other, vertically slotted slides mounted in 110 said guides, a rack having divergent sides disposed between the pairs of guides and having trunnions at its axial center having sliding engagement with said slots, links pivotally connected to the upper ends of the 115 slides and pivotally connected to the rack rearward of the axial center thereof, cables extending downward from the upper ends of the guides operatively connected to the axial center of the rack and to a source of power 120 whereby the cables may be retracted to raise the slides and racks, and means for limiting the upward movement of the slides in said guides.

8. A stacker including a base, a pair of 125 vertically disposed guides mounted on the base and longitudinally spaced from each other, vertically slotted slides mounted in said guides, a rack having divergent sides disposed between the pairs of guides and 130

- having trunnions at its axial center having sliding engagement with said slots, links pivotally connected to the upper ends of the slides and pivotally connected to the rack 5 rearward of the axial center thereof, cables extending downward from the upper ends of the guides operatively connected to the axial center of the rack and to a source of power whereby the cables may be retracted to raise 10 the slides and racks, and means for limiting the upward movement of the slides in said guides, and comprising pins adjustable at different elevations through said guides and in the path of movement of the slides.
- 15 9. A stacker including a base, vertically disposed pairs of longitudinally spaced guides mounted upon the base, a rack having divergent sides disposed between the pairs of guides, longitudinally slotted slides operatively engaging the guides, the rack having trunnions at its axial center passing through the slots of the slides, links pivotally connected to the upper ends of the slides and extending downward and rearward and pivotally connected to the rack rearward of its axial center, adjustable means for limiting the upward movement of the slides, means connected to the axial center of the rack for raising and lowering it, and means for pre-
- venting the downward movement of the 30 slides after they have engaged said adjustable means comprising a pair of latches disposed on the face of each slide, the lower ends of the latches being downwardly divergent, the guides having notches with which the 35 latches engage and wedges carried by the trunnions of the racks and urging said latches apart and into said notches when the trunnions move upwardly independently of the slide. 40
10. A stacker including a vertically movable and rotatably mounted rack having divergent sides, means for applying power to the rack to hoist it to a predetermined elevation, a stop impeding the upward movement of one side of the rack beyond a predetermined elevation, said stop permitting the middle of the rack to continue its upward movement under the action of the power applying means, to thereby rotate the 50 rack to a dumping position.

In testimony whereof I hereunto affix my signature in the presence of two witnesses.

OLIVER P. WENTWORTH.
